UNITED STATES PATENT OFFICE.

WILLIAM N. WHITELEY, OF SPRINGFIELD, OHIO.

CAST WHEEL.

SPECIFICATION forming part of Letters Patent No. 328,736, dated October 20, 1885.

Application filed August 31, 1885. Serial No. 175,825. (No model.)

To all whom it may concern:

Be it known that I, WILLIAM N. WHITELEY, of Springfield, county of Clark, State of Ohio, have invented a new and useful Improvement 5 in Cast Wheels, of which the following is a specification.

My invention relates to cast-metal pulleys or wheels, and particularly to main wheels and supporting-wheels, &c., of harvesting-machines, and generally to carrying-wheels, especially of agricultural implements, made of cast-iron, malleable iron, or cast-steel; and it consists in casting the wheel all in one piece, but having the rim divided in a peculiar way 10 in one or more places, which are afterward riveted or otherwise securely fastened.

The object of my invention is to so construct a wheel that it may be cast of malleable iron, ordinary cast-iron, or steel in such a manner that upon its cooling and shrinking the rim shall not break or become distorted and warped out of a perfect circle. All cast-metal wheels with heavy rims are subjected to great 20 peripheral tension, owing to the unequal cooling of the exterior and interior metal. This makes the rim brittle and liable to break under hard usage. The rim is therefore divided, so that it can shrink without strain; but the point where the meeting ends of the divided 25 rim are secured together is less stiff than that part between spokes, because it is discontinuous, and the strength of the coupling-bolts is the measure of the mutual support. I can compensate this weakness by casting the ends

30 on each side of the division with a greater radius than the circle of the wheel, and afterward forcibly reducing said ends to conform to the circle of the wheel by means of a tension-rod or otherwise. When so forcibly reduced to the circle of the wheel, these ends are under permanent stress, and will not yield 35 further until the force applied exceeds said permanent stress. This is a well-known principle of permanent stress applied to truss-bridges. In practice I find it sufficient and preferable for the purposes of a harvester-wheel to produce said permanent stress by making one end of the division of greater and

40 the other end of less radius than the radius of the wheel, and then forcibly springing said ends together and securing them together by

bolts. This method is shown in my drawings; but I do not confine myself thereto.

In the drawings, Figure 1 is a front elevation, and Fig. 2 an edge view, of a harvesting-machinewheel constructed upon my plan. Fig. 3 is a perspective view showing the method of fastening the divided rim. Fig. 4 is a front elevation, and Fig. 5 an edge view, of an ordinary pulley, showing the method of dividing 55 and afterward fastening the rim.

Similar letters refer to like parts in the several views.

The construction of harvester and other carrying-wheels upon my plan is as follows: 65

The pattern from which mold is made does not conform to a perfect circle. In the interval between the spokes or arms where a division in the rim occurs one portion of the rim (from A to B) is formed with a longer radius 70 than the normal radius of the wheel, as shown by the dotted line c d, while that portion of the rim from B to E is formed with a shorter radius than the normal radius of the wheel, as shown by the dotted line f g. On the opposite 75 edge of the rim the form of construction is reversed, the portion from A to B is formed with the short, and from B to E with the long, radius. The ears h h cast upon those portions of the rim having the shorter radii, and overlapping the portions having the longer radii, are firmly riveted or otherwise secured thereto, as shown at M, the rim then assuming the form of a perfect circle.

In the construction of other wheels having 85 a plain face (see Figs. 4 and 5) the lap runs straight across the rim and is riveted or otherwise securely fastened, as before mentioned, while in addition the ear k is cast integral with the web of the rim, and an additional rivet or 90 other suitable fastening applied, as shown at F, Fig. 4.

By my method of constructing these wheels I am enabled to make the several parts, especially the rim, much lighter than formerly, 95 and while it possesses all the requisite strength there is no bending, distortion, or breaking of the rim from shrinkage or cooling after it is cast.

Having thus described my invention, what 100 I claim as new is—

1. A wheel for harvesters and other purposes,

constructed of cast metal, having the rim divided in one or more places with the ends diverging from the circle of the wheel and under permanent stress by being forcibly bent and held in position coincident with said circle, substantially as described, and for the purposes specified.

2. A pulley or other wheel having a plain face and constructed of cast metal having the rim divided in one or more places with one end of greater and the other end of less radius

than the circle of the wheel and under permanent stress by being forcibly brought together and secured, substantially as described, and for the purposes set forth.

In testimony whereof I have hereunto set my hand this 20th day of August, 1885.

WILLIAM N. WHITELEY.
